UNITED STATES PATENT OFFICE.

THOMAS H. WILLIAMS, OF UTICA, NEW YORK, ASSIGNOR OF ONE-HALF TO
THOMAS WHEELER, OF SAME PLACE.

FOLDING STEPS OR STAIRS FOR LIFT-BRIDGES.

SPECIFICATION forming part of Letters Patent No. 616,515, dated December 27, 1898.

Application filed January 8, 1898, Serial No. 666,035. (No model.)

To all whom it may concern:

Be it known that I, THOMAS H. WILLIAMS, of Utica, in the county of Oneida and State of New York, have invented certain new and useful Improvements in Folding Steps or Stairs for Lift-Bridges, &c.; and I do hereby declare that the following is a full, clear, and exact description of the invention, which will enable others skilled in the art to which it applies to make and use the same, reference being had to the accompanying drawings, and to the letters and figures of reference marked thereon, which form part of this specification.

Figure 1 shows a side elevation of my improved folding steps or stairs applied to a raising and lowering bridge with the parts in the position which they assume when the bridge is elevated. Fig. 2 shows the same with the parts in the position which they assume when the bridge is lowered. Fig. 3 shows a plan view of the device as shown in the previous figures, portions of the construction being broken out in order to exhibit details of the construction. Fig. 4 shows a side elevation of one of the risers attached to the bridge in connection with a cross-section of one of the steps or treads and details of slides or movable section of fence or picket work at the ends of the steps. Fig. 5 shows details of the horizontal step-support on which the steps rest when the bridge is down, in connection with the cross-section of the step.

Referring more particularly to the reference letters and figures in a description of the device, A indicates a rising-and-falling bridge such as would be used over a canal or any similar place.

B indicates the wall or abutment on which the bridge is supported when down in its lowered position.

C indicates a pit or cavity formed in the abutment, while D indicates the fixed portion or wall of the pit on the rear.

To the end of the bridge A is secured a pair of fixed risers 1, similar to the risers employed in the stairs and offset, as shown, to form supports for a suitable number of steps or treads similar to the risers of stairs. On the upper face of each of the offsets or steps there is provided a point or center 1^a, as indicated, and the risers are adapted when the bridge

is down, as shown in Fig. 2, to enter the pit C in the abutment. In order to guide and steady the risers and bridge, there may be provided on the lower end of each of the risers 55 2 a roller or wheel 3, adapted to run against a vertical way or track 4 on the side of the pit. Spanning the pit and suitably located are a pair of girders 5, which are provided with a suitable number of recesses or notches 60 5^a in their upper edges to receive the depending portions 6^a of the steps or treads 6. These girders 5 are also provided with centers or points 5^b, adapted to engage in suitable depressions on the under side of the step 6 65 and center and properly locate the steps when they are at rest on the girders. In order to strengthen and support the outer ends of the risers 1, particularly where a large number of steps and a considerable length of 70 riser is employed, I provide a cable 7, which is secured to the bridge A at 8, preferably by an adjustable fastening device, as an eyebolt and screw, as shown, and passed thence under a fixed pulley 9 on one end of the girder 75 5, and thence over a fixed pulley 10 on the other end of the girder 5 to the lower outer end of the riser, where it is secured by a suitable means, as an eyebolt and screw 11. To provide a suitable guide and holder for the 80 several steps and also at the same time provide a suitable fence or barrier at either end of the steps, I provide, secured in each step 6, a pair of vertical rods 12 13. This pair of rods may be connected at their upper ends or 85 made to conform to any design and appearance with the barriers or fence on the approaching walk at 14, as well as on the bridge, if any such are provided, which is the usual practice. These vertical rods 12 and 13 on 90 each step form slides or ways for guiding the movement of the step and preventing its removal or displacement. The rods 12 and 13 on the lower step, as shown, run freely through eyes formed in the fixed portion 15 95 of the walk-barriers and have secured thereto connecting-pieces 16 and 17. The piece 17 has an eye in one end which slides freely on the fixed rod 18, secured on the walk-abutment, while the piece 16 has eyes which receive the vertical rods 12 and 13 of the next step, and this construction is carried from

step to step until it reaches a fixed rod 19 on the end of the bridge, where the last sliding movement to permit the rise and fall of the steps is provided for, as shown.

5 The operation of the device is very simple. As the bridge goes up from the position shown in Fig. 2 toward the position shown in Fig. 1 the various offsets on the risers 1 pick up the steps one by one as they are reached, the points 10 or centers 1^a entering the depression in the under side of the step provided to receive them and centering and locating the step properly. The rods, as 12 and 13, slide in the guides, and when the complete rise has been made 15 the parts have changed from the position shown in Fig. 2 to that shown in Fig. 1. When the bridge goes down, the steps, beginning with the lower one, come to rest on the girders 5, whereon they are properly centered 20 and located by the projecting points or centers 5^b entering suitable recesses provided therefor in the under side of the step, and the vertical guide-rods 12 and 13 on the step slide in their supports until the bridge assumes 25 the position shown in Fig. 2.

The supporting-cables 7 and the pulleys used in connection therewith may be omitted where a small number of steps only are to be used, and in such case it would probably be 30 advisable to do so.

While the description has been given with reference to the specific use of a lift-bridge, in order to more clearly and satisfactorily describe its operation it is clear that the device is equally useful wherever a similar set of folding steps or stairs is useful or desirable. It is also evident that the end barriers on the steps, and particularly the vertical guides 12 and 13, may be entirely omitted or 35 made single instead of double, as shown. In case these guide-rods 12 and 13 on each step are entirely omitted it would be preferable to much extend or enlarge the points or projections 1^a on the risers 1 and 5^b on the girders 40 5 even to the extent of projecting somewhat through openings provided in the ends of the steps. It is also evident that the dependent portion 6^a of each step may be omitted, like- 45 wise the notches or recesses 5^a in the upper 50 edge of the girder 5, or the construction may be modified by omitting the notches or recesses 5^a in the girder and providing notches

or recesses in the dependent portion 6^a of the steps for receiving the girders.

What I claim as new, and desire to secure 55 by Letters Patent, is—

1. In folding steps, the combination of rising-and-falling risers having offsets adapted to support the steps, fixed girders also adapted to support the steps, and the steps, substantially as set forth. 60

2. The combination of a vertically-movable riser having an offset adapted to support the step, a stationary step-support and a step, substantially as set forth. 65

3. The combination of a vertically-movable riser having an offset adapted to support a step, a fixed support for the same step, the step and guides or ways for directing and securing the step, substantially as set forth. 70

4. The combination of a rising-and-falling riser adapted to support a step, a step, a fixed support for the step and a supporting device for the projecting end of the riser, consisting of a cable connected at each end of the 75 riser and passing over a pair of intermediate pulleys substantially as shown.

5. In folding steps or stairs, the combination of rising-and-falling risers having offsets adapted to support the steps, fixed girders also adapted to support the steps and having notches or recesses therein, and the steps 80 having depending portions.

6. A rising-and-falling step-support, a fixed step-support and a step combined, substantially as set forth. 85

7. A rising-and-falling step-support, a fixed support for the step, a step and guides or ways for securing and directing the step, substantially as set forth. 90

8. The combination of the rising-and-falling risers having offsets or shoulders for receiving the steps, a stationary or fixed support for receiving and supporting the steps, the steps and slides or guides connected with 95 each step and constituting also a barrier at the end of the step, substantially as set forth.

In witness whereof I have affixed my signature, in presence of two witnesses, this 5th day of January, 1898.

THOMAS H. WILLIAMS.
